S. HOUGH.
CUSHIONED ARMOR.
APPLICATION FILED MAR. 28, 1917.

1,262,346.

Patented Apr. 9, 1918.

UNITED STATES PATENT OFFICE

SAMUEL HOUGH, OF ATCO, NEW JERSEY, ASSIGNOR OF ONE-THIRD TO WILLIAM H. PITTEINGER AND ONE-THIRD TO GORDON GRAY, BOTH OF CAMDEN, NEW JERSEY, AND ONE-THIRD TO ELECTRIC CUSHIONED ARMOR COMPANY, A CORPORATION OF NEW JERSEY.

CUSHIONED ARMOR.

1,262,346.

Specification of Letters Patent.

Patented Apr. 9, 1918.

Application filed March 28, 1917. Serial No. 157,883.

To all whom it may concern:

Be it known that I, SAMUEL HOUGH, a citizen of the United States, residing at Atco, in the county of Camden and State of New Jersey, have invented new and useful Improvements in Cushioned Armor, of which the following is a specification.

My invention relates to new and useful improvements in uncushioned armor, and 10 has for its object to provide a device of this character which may be readily and quickly applied to vessels of the above character and construction to protect the same against an impact of torpedoes, mines, sub-marines or 15 other missiles, which may be used for the destruction of vessels.

A further object of the invention is to provide a simple and unique construction of armor for vessels which will absorb the shock 20 incident to a (hit) by a missile of any character, and prevent the explosion of such missile, said armor being so arranged on the sides of the vessel as to extend above and below the water line sufficient distance to 25 protect the vessel against missiles traveling or floating on top of or beneath the surface of the water.

Another object of the invention is to provide a cushioned armor for vessels which may 30 be lowered in time of need and raised while traveling through safety or neuter zones and when entering the harbors or rivers of an opening port, so that the armor will not interfere with the docking of the vessel and 35 also permit another vessel to run alongside of the same for loading or unloading.

A still further object of the invention is 40 to provide a cushioned armor, hinged to the side of a vessel in any suitable manner, said armor comprising two spaced frames, movable toward each other, and having arranged between them suitable resilient shock absorbing or cushioning elements. Said elements, preferably each consisting of a cylinder having 45 a piston located therein, normally forced outward by a spring, said cylinder also containing a liquid, such as glycerin, adapted to be forced out of the cylinder into a liquid chamber in communication with the cylinder 50 through a restricted port.

Said liquid chamber having an outlet for the air, said outlet being provided with

means for regulating the flow of air therethrough.

With these ends in view, this invention 55 consists in the details of construction, a combination of elements hereinafter set forth, and then specifically designated by the claims.

In order that those skilled in the art to 60 which this invention appertains, may understand how to make and use the same, I will describe its construction in detail, referring by numerals to the accompanying drawings forming a part of this application in which— 65

Figure 1, is a fragmentary side elevation of a vessel illustrating in end elevation one of the members forming a part of my cushion armor.

Fig. 2, is a fragmentary side elevation of 70 a vessel showing a number of armor sections applied thereto, the different sections having parts thereof broken away to clearly illustrate the construction.

Fig. 3, is an enlarged detailed section of 75 one of the resilient shock absorbing or cushioning elements showing parts of the co-operating structure.

In carrying out my invention as here embodied, 2 represents the hull of a vessel, having secured to the outer surface of the shell a suitable distance below the gunwale brackets or hangers, 3 which may be in horizontal alignment, as shown, or they may be arranged in sets and located in staggered relation. In adjacent brackets or hangers, 3 is mounted or journaled a shaft 4 and where all of the brackets or hangers 3 are in horizontal alignment, the shaft may be secured in all of them, and then bent to conform to the shape of the vessel hull. On each shaft or the sections of shaft between co-operating brackets or hangers are journaled a plurality of supporting arms 5, either arranged in pairs or sets of three or more, and these arms support the cushioned armor 6 preferably composed of a number of parts or members 7. Each of the parts or members 7 consists of the inner frame 8, preferably of wood, and this is built to conform to the outer contour of the shell of the vessel's hull as plainly shown in Fig. 1.

To this inner frame are hinged or pivoted the outer ends of the piston rods 9 as by

hinge brackets 10, fastened to said inner frame by means of bolts 11 or their equivalent. The piston rod 9 projects into a cylinder 12 secured to the outer frame 13, 5 and said piston rod carries on its inner end, a piston 14 slidably mounted within the cylinder and normally forced toward the free or outer end of the cylinder by suitable resilient means 15, such as a spring located 10 within the cylinder and resting against an end thereof, and the piston 15.

Located adjacent the cylinder, is a fluid chamber 16 having communication with the interior of the cylinder through a restricted 15 opening 17, and said fluid chamber has connected thereto, an outlet pipe 29 leading to the atmosphere. The passage through this outlet pipe is controlled by valve or pet cock 18. As each of the parts or members 20 of the cushioned armor is provided with a plurality of shock absorbing or cushioning elements 19 consisting of the cylinders and their analogous elements, and since each cylinder is provided with a liquid 25 chamber 16, said chambers may be connected in series or sets by an outlet pipe and its branches as plainly shown in Fig. 2.

The outer frame of the armor consists of an iron or other metal skeleton frame 20 having an inturned flange 23 for strengthening the same to overcome the possibility of buckling when buffeted by high seas. This frame is suitably braced by a strut 21, and this skeleton frame is provided with a 35 filler 22 of wood or other suitable material, and the entire outer face of this outer frame is incased or covered by an armor plate 24 of steel or other suitable metal, such as used by the navies of different countries as armor 40 plate for war vessels. Each of the members or sections 7 of the cushion armor 6 are supported by the supporting arms 5 as hereinbefore described, and these arms are 45 preferably secured to the outer frame 13 at the upper edge thereof as shown in Fig. 1.

When it is desired to raise the different sections of the armor into the inoperative position, the flexible cables 25 are drawn in, in any suitable and well known manner as 50 by a winch, (not shown) the outer ends of these cables each being attached to the lower ends of the different sections or members of the armor as by bridles 26, and when the armor is to be placed in operative position, the cables 25 are slackened and the cables 27 are drawn taut in any suitable and well known manner which will draw the armor sections snugly against sides of the vessel since said cables are attached to 60 the lower ends of the different sections and pass over suitable guides 28 carried by the vessel's hull in suitable positions to guide the pull upon the cables in the proper direction for accomplishing the above result.

65 In practice, when a vessel carrying my

improved cushioned armor is traveling anywhere where it is likely to be torpedoed or fired upon or strike a mine, the different sections of the armor are lowered to the operative position as shown, and if a missile 70 of any character should strike the vessel in the region of the armor, said missile will come in contact with the armor plate 24 which will tend to give away or move toward the vessel's hull. This action of the 75 missile upon the armor plate will cause the outer frame to move toward the inner frame and slide the pistons of the resilient and cushioning elements within their cylinders against the action of the 80 springs 15 and cause the liquid contained within said cylinders to be forced out of the same very slowly through the restricted openings 17 into the liquid chambers 16, thereby absorbing or cushioning the 85 shock incident to the impact of the missile upon the armor. When the cushioned armor is in use, the valves or pet cocks 18 are opened to permit the escape of air from the liquid chambers 16, when, because of some 90 impact upon the armor, the liquid is forced from the cylinders to the liquid chambers but when the armor sections are to be raised to their inoperative positions, the pet cocks or valves 18 are closed to prevent the escape 95 of the liquid from the liquid chambers. The liquid used in the cylinders may be glycerin, a suitable compound, water or anything else which may be found practicable for the purpose. Of course, I do 100 not wish to be limited to the exact details of construction as here shown, as these may be varied within the limits of the appended claims without departing from the spirit of my invention.

Having thus fully described my invention, what I claim as new and useful, is—

1. A cushioned armor for vessels consisting of two members and resilient means connected with said members for normally forcing them apart and absorbing the shock incident to the impact of an object against one of them, said resilient means comprising a cylinder, a piston therein, a piston rod connected to the piston and projecting through one end of the cylinder, a spring for normally forcing the piston outward, a liquid chamber having communication with the cylinder through a restricted opening, a controlled outlet leading from the liquid chamber, and a liquid contained in the cylinder and adapted to pass into the liquid chamber under certain conditions.

2. In a device of the character stated, the combination with a vessel of a cushioned armor hinged to the outside of the vessel comprising a plurality of sections, each section consisting of two spaced members and cushioning elements located between and attached to said members, cables for raising 125

130

said sections into inoperative positions and other cables for drawing said sections into operative positions.

3. In combination with a vessel, a cushioned armor comprising a plurality of sections, each section consisting of an inner frame shaped to conform to the outer contour of the hull of the vessel, an outer frame approximately parallel with and spaced 10 from the first named frame, and resilient means located between and attached to said frames, brackets or hangers carried by the vessel, means supported by said hangers and supporting arms carried by the outer frame 15 of each section, said arms being journaled on said means for hinging the armor to the vessel.

4. In combination with a vessel, a cushioned armor comprising a plurality of sections, each section consisting of an inner frame shaped to conform to the outer contour of the hull of the vessel, an outer frame approximately parallel with and spaced 20 from the first named frame, said outer frame 25 consisting of a metal skeleton frame, having inturned flanges, a strut for bracing the same, a filler within said skeleton frame and an armor plate covering the outer face of the skeleton frame and its filler, a plurality 30 of cylinders carried by the outer frame and

located within the space between the inner and outer frames, pistons within said cylinders, piston rods carried by said pistons and projecting through the free or outer ends of the cylinders, hinge brackets secured to the 35 inner frame for hinging the outer ends of the piston rods thereto, springs within the cylinders for normally forcing the pistons outward, a liquid chamber located adjacent each cylinder and having communication 40 therewith through a restricted opening, liquid contained in the cylinders and adapted to be forced into the liquid chambers upon the impact of an object against the armor plate, an air outlet leading from each of said 45 chambers means for controlling said outlets, hangers projecting from the hull of the vessel, a shaft supported by said hangers, a plurality of supporting arms carried by each armor section and journaled on the shaft, 50 cables attached to the lower ends of the sections whereby said sections may be raised, guides carried by the hull of the vessel and cables attached to lower ends of the sections and running through said guides whereby 55 the sections may be drawn snugly against the sides of the vessel.

In testimony whereof, I have hereunto affixed my signature.

SAMUEL HOUGH.
